UNITED STATES PATENT OFFICE.

JOSEPH ALBERT DEPORT, OF PARIS, FRANCE.

HYDRAULIC-BRAKE APPARATUS FOR ORDNANCE.

SPECIFICATION forming part of Letters Patent No. 565,607, dated August 11, 1896.

Application filed May 31, 1895. Serial No. 551,240. (No model.) Patented in England April 19, 1895, No. 7,874.

To all whom it may concern:

Be it known that I, JOSEPH ALBERT DEPORT, a citizen of the Republic of France, residing in Paris, France, have invented certain new and useful Improvements in Hydraulic-Brake Apparatus for Utilizing the Energy Developed by the Recoil of Ordnance, (being the subject-matter of Letters Patent in Great Britain, No. 7,874, dated April 19, 1895,) of which the following is a specification.

My invention relates to improvements in the hydraulic brakes applied to ordnance for checking the recoil, the object of my invention being to utilize a portion of the energy of the recoil, not merely for obtaining the automatic return of the gun to battery, but also for employing this energy for the aiming or charging of the gun, while at the same time assuring an effective operation during the recoil and during the return of the gun to battery. For this purpose I so arrange the hydraulic brake that during a considerable part of the recoil the liquid compressed by the piston passes wholly or partially into accumulators, where it is made either to compress springs or air, passing for this purpose through one or more check-valves, which retain the fluid-pressure forced in, so as to store it up for subsequent use. At the end of the said portion of the recoil the liquid forced by the brake no longer passes through the said valves into the accumulator, and the brake then acts as an ordinary hydraulic brake for limiting the recoil to the prescribed extent of travel.

The liquid under pressure in the accumulators may serve for running the gun into position again when this is not effected by gravity, and it may also be utilized in various hydraulic apparatus serving for pointing the gun or for loading or maneuvering the same, after which the liquid is made to pass back to the brake apparatus through a conduit provided with a check-valve arranged to close during the recoil.

A chamber or reservoir for receiving the overflow from the accumulators and the spent liquid from the said subsidiary hydraulic apparatus is generally interposed in the channel between the said apparatus and the hydraulic brake, from which chamber the liquid is then supplied to the brake.

In some cases I so arrange the brake as to,

cause it to compress air during the recoil, which is then used either for running the gun into position or for expelling the explosion gases remaining in the gun after firing, or for any other purposes.

In order that my said invention may be readily understood, I have shown on the accompanying drawings, by way of example, various arrangements for carrying the same into effect.

Figure 1 is a longitudinal section of one form of my hydraulic brake, and shows in connection a diagram of the accumulator G, the hydraulic apparatus H, and the overflow chamber or reservoir I. Fig. 2 is a longitudinal section of an ordinary construction of hydraulic brake, wherein the piston-rod is tubular and receives a fixed stem, modified according to my invention. Fig. 3 illustrates a further feature of my invention, being a construction based upon Fig. 2, with the additional provision of means for utilizing the stored hydraulic power for effecting the running out of the gun to battery. Fig. 4 shows in elevation the brake-cylinder of Fig. 3 and shows in section the breech portion of the gun and the rear portion of the hollow piston-rod, illustrating a further feature of my invention whereby compressed air is injected into the gun after firing for expelling gases of combustion. Fig. 5 is a section on a larger scale of the compressed-air admission shown in Fig. 4. Fig. 6 is a sectional view showing a modification of the brake-cylinder illustrated in Fig. 3. Fig. 7 is a sectional elevation illustrating an apparatus embodying all the features of my invention, the hydraulic-brake apparatus being in section on the line 7-7 in Fig. 9. Fig. 8 is a plan, half in horizontal section, on the line 8-8 in Fig. 9. Fig. 9 is a transverse section on the line 9-9 in Fig. 8.

In all the figures the parts are in the position assumed immediately after the commencement of the recoil.

Referring, first, to Fig. 1, A is the piston, which is attached to the cannon. B is the hydraulic cylinder, and C is the by-pass channel in this cylinder, having a progressively-decreasing section. Sometimes the piston is provided with an orifice closed by a check-valve D, which opens during the return to battery.

I connect laterally to the brake-cylinder a duct E, having a check-valve F, arranged to close during the recoil by the pressure of the liquid forced out by this piston. This duct 5 connects to one or several accumulators, (shown at G,) operating either by the compression of springs or by compressed air, (the latter being shown in Fig. 8,) and which store the liquid driven out by the piston while the latter is traveling from its first position to the branching off of the conduit E. From these accumulators lead ducts which extend to the apparatus of utilization, such as presses or hydraulic cylinders, (indicated at H,) and 15 which are employed in the aiming or the re-loading of the cannon. The liquid flowing from these apparatus runs into an overflow-tank, cistern, or other reservoir I, which also receives, if necessary, the excess of liquid 20 from the accumulators which flows over through a small tube K. This reservoir I communicates with the brake by a conduit L, provided with a valve M, arranged to close during the recoil, and to open during the 25 movement to battery.

This brake operates as follows: While the piston is moving back from its initial position of rest to the branching off of the conduit E the valves D and M are closed. The brake 30 forces into the accumulators past the valve F the liquid which is displaced by the piston, except a small quantity which leaks past the piston through the channel C. From the moment that the piston passes the valve F to 35 the end of its travel the valve F is outside of the action of the liquid compressed by the piston, and it is closed by the pressure from the accumulators. During the second part 40 of the travel of the piston the brake becomes in effect an ordinary brake, the channel C progressively decreasing and coming to an end before the piston reaches the end of the cylinder, so that the piston cushions upon 45 the liquid retained in the end of the cylinder, so as to finally arrest the recoil of the cannon. During the return movement to battery the valve M opens and the reservoir I permits liquid to flow out into the body of 50 the cylinder for replacing that which was previously forced into the accumulator. Toward the end of this movement the piston A encounters the liquid which had leaked around it during the recoil and compresses it, whereupon this liquid passes through the 55 channel C, as well as by the orifice closed by the valve D; if this orifice is provided, so that this liquid serves the purpose of moderating the speed of the return of the gun to battery.

The purpose of the reservoir I is to afford 60 a supply for assuring the refilling of the brake-cylinder, notwithstanding the variable consumption of the apparatus of utilization. Hence the reservoir may be interposed or 65 simply branched on the conduit returning to the brake or on the brake itself.

As another example of hydraulic brake to which my invention is applicable I have in-

dicated in Fig. 2 a brake in which the piston-rod is made tubular and has a fixed stem P projecting into it for regulating the running 70 out of the gun to battery. This figure shows the arrangement required to adapt my invention to this type of hydraulic brake. These conditions are the same as in the preceding case. In this construction the by-pass channel C is shortened to restrict it to that part 75 of the brake-cylinder traversed during the last part of the travel of the piston.

Fig. 3 shows an example of the application of my system to a hydraulic brake which 80 is constructed for effecting the running out of the gun to battery by the action of the liquid-pressure stored in the accumulators. The brake shown in Fig. 3 is analogous to that shown in Fig. 2. The piston-rod is hollow and forms a hydraulic cylinder A' for the piston P, formed on the fixed piston-rod, this rod being provided with a central channel Q, which is in permanent communication with the compressed liquid in the accumulator. It is seen that in this arrangement 85 the means for utilizing the energy of the recoil are the same as in the preceding.

I sometimes construct this brake in such manner as during the movement to battery 90 to furnish in addition compressed air, which I employ for purging the gun of offensive gases before the opening of the breech. The connections required for this purpose are shown in Fig. 4. During the recoil the vacuum 95 which tends to form in the cylinder A' is relieved from the outer air, which opens the check-valve R and fills this cylinder. During the return to battery the valve R closes, the 100 air is compressed and lifts the valve S, which is provided in the cannon and placed just in front of the obturator or gas-check T. This 105 valve is restored to place by its weight, aided, if necessary, by the action of a spring or else by the act of introducing the projectile. 110 The valve is shown on a larger scale in Fig. 5.

Figs. 7, 8, and 9 show in combination the 115 complete apparatus provided with all the features of my invention. The same letters are applied as in the preceding figures. The construction of brake-cylinder here shown is the same as that shown in Fig. 3, with the addition of the means for pumping air into the barrel of the cannon during the return to battery shown in Fig. 4.

The construction of accumulator shown in Fig. 6 operates by the utilization of compressed air for expelling the water, a movable piston g being provided as a partition between the water-chamber and the compressed-air chamber. The hydraulic utilization apparatus H is here shown as a hydraulic cylinder and piston connected to the gun-carriage in such manner as to tilt the latter in aiming the gun.

Instead of putting the arrangement for return to battery in the central part of the brake and the means for checking the recoil in the annular exterior portion, as shown in Fig. 3,

the reverse arrangement may be adopted. This arrangement is shown in Fig. 6. In this brake the annular space exterior to the hollow cylinder A' is in permanent communication with the accumulator and serves to assure the return to battery. The recoil-brake is arranged in the interior of this cylinder by means of the central piston-rod P and the bypass groove C. During the recoil of the hollow piston A' the liquid compressed in the interior brake flows out through the orifice E', through the bore of the piston-rod, and lifts the valve F, flowing thence by the duct E to the accumulator. The flow of liquid into the accumulator ceases when the piston arrives at the opening E', and from this moment and until the end of the recoil the brake apparatus is an ordinary brake having a channel C of progressively-diminishing capacity. The re-entry into the brake of the liquid from the reservoir and the apparatus of utilization is effected by the conduit L, provided with a valve N, arranged to close during the recoil and to open during the return to battery.

25 By these examples it is seen that the mode of organization of the hydraulic brakes for economizing the energy of the recoil after my system consists in each case in dividing the course of the brake into two parts by means 30 of a lateral orifice in communication with the accumulator, and provided with a check-valve. During the first part of the course, which extends from the initial position of the piston until the instant when it reaches this 35 orifice, there is forced into the accumulator the liquid displaced by the piston. From this instant the charging of the accumulator ceases and the brake becomes an ordinary hydraulic 40 brake with a by-pass of progressively-decreasing capacity, capable of effectively taking up the remaining energy of recoil.

What I claim is—

1. A hydraulic-brake apparatus for ordnance, comprising a brake-cylinder and piston, a lateral opening from said cylinder having an outwardly-opening check-valve and located to be passed by the piston before the end of the movement of recoil, and an accumulator connected to said opening to receive the liquid which passes said valve, whereby during the recoil the piston forces liquid out of said lateral opening and stores its pressure in said accumulator until the piston passes said opening, and during the remaining travel of the piston in said cylinder it acts as a simple hydraulic brake.

2. A hydraulic-brake apparatus for ordnance, comprising a brake-cylinder and piston, a lateral opening from said cylinder having an outwardly-opening check-valve and located to be passed by the piston before the end of the movement of recoil, a by-pass channel for permitting a limited flow of liquid around the piston during the remainder of the movement of recoil, and an accumulator connected to said opening to receive the liquid which passes said valve, whereby during the

recoil the piston forces liquid out of said lateral opening and stores its pressure in said accumulator until the piston passes said opening, and during the remaining travel of the piston in said cylinder it acts as a simple hydraulic brake regulated by the action of said by-pass channel.

3. A hydraulic-brake apparatus for ordnance, comprising a brake-cylinder and piston, a lateral opening from said cylinder having an outwardly-opening check-valve and located to be passed by the piston before the end of the movement of recoil, an accumulator connected to said opening to receive the liquid which passes said valve, and a hydraulic apparatus worked by pressure from said accumulator, whereby during the recoil the piston forces liquid out of said lateral opening and stores its pressure in said accumulator until the piston passes said opening, and during the remaining travel of the piston in said cylinder it acts as a simple hydraulic brake.

4. A hydraulic-brake apparatus for ordnance, comprising a brake-cylinder and piston, a lateral opening from said cylinder having an outwardly-opening check-valve and located to be passed by the piston before the end of the movement of recoil, an accumulator connected to said opening to receive the liquid which passes said valve, a reservoir for the surplus or spent liquid, and a conduit for drawing liquid from said reservoir to the brake-cylinder to refill the latter during the movement of running out the gun to battery.

5. A hydraulic-brake apparatus for ordnance, comprising a brake-cylinder and piston, a lateral opening from said cylinder having an outwardly-opening check-valve and located to be passed by the piston before the end of the movement of recoil, an accumulator connected to said opening to receive the liquid which passes said valve, a reservoir for the surplus or spent liquid, and a conduit for drawing liquid from said reservoir to the brake-cylinder to refill the latter during the movement of running out the gun to battery, and a check-valve for said conduit adapted to open for drawing liquid into the cylinder and to close during the recoil.

6. A hydraulic-brake apparatus for ordnance, comprising a brake-cylinder, a piston movable therein having a hollow rod, a tubular fixed stem in said hollow rod formed with a piston fitting the same, whereby are constituted two cylinders with pistons the one exterior to said hollow piston-rod and the other within the same, a lateral opening from one of said cylinders having an outwardly-opening check-valve and located to be passed by the piston thereof before the end of the movement of recoil, an accumulator connected to said opening to receive the liquid which passes said valve, and a conduit from said accumulator communicating with the other of said cylinders and adapted to conduct liquid under pressure from said ac-

cumulator to said cylinder for restoring the parts and thereby running out the gun to battery.

7. A hydraulic-brake apparatus for ordnance, comprising a brake-cylinder and piston, an accumulator connected therewith, a secondary cylinder, an air-admission check-valve to the latter, and a valved air-outlet conduit therefrom leading to the bore of the gun, combined and adapted to compress air in said secondary cylinder during the movement of the gun to battery, and to admit said compressed air to the breech portion of the gun for expelling the gases of combustion.

15 8. A hydraulic-brake apparatus for ordnance, comprising a brake-cylinder, a piston movable therein, a hollow piston-rod therefor

its interior forming a secondary cylinder, a fixed piston in said rod having a stationary stem, said hollow piston-rod provided with an air-inlet check-valve adapted to admit air during the recoil, and with a valved conduit leading thence to the breech portion of the gun, whereby the air compressed in said hollow rod during the running out to battery is caused to enter the bore of the gun for expelling the gases of combustion.

In witness whereof I have hereunto signed my name in the presence of two subscribing witnesses.
